(57) **CLAIM**

The ornamental design for an electrically heated travel mug, as shown and described.

DESCRIPTION

FIG. 1 is a front perspective view of an electrically heated travel mug, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of a partial electrical cord and plug in FIG. 1 and electrical socket in FIG. 4 depict portions of the electrically heated travel mug that form no part of the claimed design.
